UNITED STATES PATENT OFFICE.

MICHAEL J. McMENAMIN AND CHARLES NIXON, OF PHILADELPHIA, AND REESE D. GREENLAND, OF BEDFORD, PENNSYLVANIA.

TRACK LIFTER.

Application filed February 27, 1924. Serial No. 695,554.

To all whom it may concern:

Be it known that we, MICHAEL J. McMENAMIN and CHARLES NIXON, residing in Philadelphia, Pennsylvania, and REESE D. GREENLAND, residing in Bedford, Pennsylvania, citizens of the United States, have invented a Track Lifter, of which the following is a specification.

Our invention relates to apparatus for raising and moving tracks.

An important object of our invention is to provide apparatus for raising and moving tracks which is characterized, particularly, by the relatively small number of men necessary for its efficient operation and by the large amount of track which can be raised and moved in any given time.

Another object of our invention is to provide track-lifting apparatus comprising a carriage movable over the track section to be lifted, clamping members for engaging the track section and hoisting mechanism operatively associated with the clamping members for raising the movable carriage as well as the track section.

A further object of our invention is to mount the clamping members in guide boxes, which are carried by the movable carriage; and to provide guiding means for the hoisting cables at the point where they enter the guide boxes.

With these and other objects and applications in mind, our invention further consists in the details of construction and operation hereinafter described and claimed and illustrated in the accompanying drawings, wherein—

Fig. 1 is a side elevational view of a preferred form of embodiment of our invention;

Fig. 2 is a top plan view of the structure of Fig. 1;

Figs. 3 and 4 are enlarged detail, longitudinal and transverse sectional views, respectively, taken on the lines III—III and IV—IV of Fig. 2; and

Fig. 5 is a perspective view of a modified form of embodiment of our invention.

In the illustrated form of embodiment of our invention shown in Figs. 1 to 4, inclusive, a movable carriage 1 comprises a pair of longitudinally extending side members 2 and 3 which are interconnected, intermediate the opposite ends thereof, by spaced transverse members 4 and 5 and cross members 6

and 7 to form a rigid construction. This structure may be mounted on spaced axles 8 and 9 which provide journals for pairs of wheels 10 and 11, respectively. The wheels 10 and 11 are adapted to rails 12 and 13 of a track section 14 which is to be moved.

A pair of guide boxes 15 and 16 are formed at each end of the movable carriage 1 immediately over the rails 12 and 13, respectively, by means of spaced vertical side members 17 and 18, the latter of which is secured to the ends of the longitudinally extending side members 2 and 3. The side member 17 may be secured in spaced relation to the side member 18 by means of spacing members 19 and 21, which define the outer ends of the guide boxes 15 and 16, respectively, and members 22 and 23, which define the inner ends of said guide boxes. A bracing member 24 may be positioned in engagement with the side member 18 at either end of the carriage 1 and it may be supported by means of members 25 and 26 which are respectively carried by the longitudinally extending side members 2 and 3. The structure forming the pairs of boxes 15 and 16 may be further secured by means of braces 27 which extend, respectively, from the under side of the side members 2 and 3 into engagement with the lower side portion of the members 18.

The portions of the members 17 and 18 constituting side walls of the several boxes 15 and 16 may be provided with aligned perforations 29 and 31, respectively, which are fitted with steel bushings 32 and 33 adapted to receive a bolt 34 constituting the pivot for arms 35 and 36 of a clamping member 37. The position of the bolt 34 is such that the lower ends of the arms 35 and 36 embrace a web portion 38 of the rails 12 and 13 when the clamping member 37 is moved into its closed position, as shown in Figs. 3 and 4. When the clamping member 37, however, is moved into the open position shown in dotted lines in Fig. 4, the lower ends of the arms 35 and 36 swing clear of the rails 12 and 13.

The upper end of the arms 35 and 36 have pivotally secured thereto links 39 and 41, respectively, a pin 42 pivotally securing together the free ends of the links 39 and 41. The pin 42 provides a mounting for a clevis 43, which engages a looped end portion 44 of a cable 45, the other end of which is

secured to a hook 46 of hoisting mechanism 47. A sleeve or guiding pulley 48 is provided for each of the four cables 45 at the point where they enter the guide boxes and it is revolvably mounted in a bracket 49 which is supported on the members 18 and 24, whereby friction and unnecessary wear in the guide boxes may be substantially avoided. In order to prevent the cables 45 from jumping the guiding sleeves 48, guards 51 may be provided which are carried by the supporting brackets 49.

In operation, assuming the hook 46 of the hoisting mechanism 47 lowered sufficiently 15 to cause the arms 35 and 36 of the clamping members 37 to lie in the dotted line position shown in Fig. 4, the carriage 1 is moved out over the track section 14 to be lifted. The hook 46 of the hoisting mechanism 47 is then 20 raised, causing the lower ends of the arms 35 and 36 of the clamping members 37 to be actuated downwardly and into engagement with the web 38 of the rails 12 and 13. The continued raising of the hook 46 causes the 25 carriage 1 as well as the track section 14 to be bodily raised and it may then be moved in any desired position.

Practical experience has indicated that should the web 38 of the rails 12 and 13 30 be covered with dirt or other material, the lower ends of the arms 35 and 36 of the clamping member 37, under the hoisting action of the mechanism 47, are positively actuated through said covering material and 35 into engagement with the web portion 38.

In Fig. 5, we have shown a simplified form of our invention comprising a rectangular frame work 52 which is supported from a hook 53 of hoisting mechanism 54 by 40 means of cables 55, the latter extending to the corners of the rectangular structure 52. A clamping member 56 extends downwardly from each of the corners of the rectangular supporting structure 52 and it is adapted to 45 releasably engage rails 57 of a track section 58 which is to be lifted.

In operation, the hook 53 is moved into position, so that the rectangular supporting structure 52 and, consequently, the clamping 50 member 56 are directly over the rails 57. When the hook 53 is raised, the clamping members 56 engage the web of the rails 57, the continued raising of the hook 53 causing the track section 58 to be lifted, as in the 55 preceding figures.

While we have shown only two forms 60 of embodiment of our invention for the purpose of illustrating the construction and operation thereof, it is apparent that various changes and modifications may be made 65 therein without departing from the spirit of our invention, we desire, therefore, that only such limitations shall be imposed thereon as are indicated in the appended claims 65 or as are demanded by the prior art.

We claim:

1. Apparatus comprising a supporting structure, a plurality of clamping devices adapted to engage a member to be lifted, hoisting means operatively associated with 70 said supporting structure, and anti-friction guiding means for said hoisting means.

2. Apparatus comprising a supporting structure, clamping devices for engaging the member to be lifted, guide boxes for said 75 clamping devices, hoisting means operatively associated with said devices, and anti-friction guiding means for said hoisting means.

3. Track-lifting apparatus comprising a 80 supporting structure, clamping devices adapted to engage the track section to be lifted, hoisting mechanism including a plurality of cables operatively associated with said clamping devices, and means for guiding 85 said cables when the latter moves relative to said structure.

4. Track-lifting mechanism comprising a carriage movable on the track section to be lifted, clamping devices for engaging said 90 track section, hoisting means including cables operatively associated with said clamping devices and guide wheels for said cables.

5. Track-lifting apparatus comprising a 95 movable carriage, a plurality of guide boxes mounted on said carriage, clamping devices supported in said guide boxes, and hoisting means including a plurality of cables operatively associated with said clamping devices. 100

6. Track-lifting apparatus comprising a movable carriage, a plurality of guide boxes mounted on said carriage, clamping devices supported in said guide boxes, hoisting means including a plurality of cables operatively associated with said clamping devices, and means for guiding said cables adjacent 105 to said guide boxes.

7. Track-lifting apparatus comprising a movable carriage having a plurality of guide boxes, a plurality of tongs having open and closed positions positioned in said boxes, each of said tongs comprising arms, a common pivot pin for said arms so supported by said guide boxes that the tong engages 110 the track only in its closed position, hoisting mechanism, and means for interconnecting said tongs and said hoisting mechanism, whereby the release of said hoisting mechanism permits a movement of the tongs into 115 their open position.

8. Track-lifting apparatus comprising a carriage movable over the track section to be lifted, a plurality of clamping devices adapted to engage said track section when in their closed position, means associated with each clamping device for guiding and supporting the same, said means being carried by said movable carriage, hoisting mechanism, a 120 plurality of cables for interconnecting said 125 prior art.

hoisting mechanism and said clamping device, and a guide wheel for each cable.

9. In combination, a track section to be lifted, a carriage movable over the same and provided with a plurality of vertically extending guide boxes, a corresponding plurality of clamping devices positioned in said guide boxes and supported by the same, hoisting mechanism, a cable interconnecting each clamping device and said hoisting mechanism, and guiding means for each cable positioned at the upper end of each of said vertically extending guide boxes.

10. Track-lifting apparatus comprising a carriage movable over the track section to be lifted and provided with a plurality of ver-

tically extending guide boxes positioned immediately adjacent to the rails of said track section, a pair of arms in each of said guide boxes, a pin pivotally connecting each pair 20 of arms to form tongs adapted to engage said rails, each of said pins being supported by the walls of said guide boxes, hoisting mechanism, a plurality of cables interconnecting said tongs and said hoisting mechanism, 25 and guide pulleys for said cables positioned at the upper end of said vertical guide boxes.
